LANTERN HOLDER FOR ROAD CROSSINGS

William A. Lowe, Wyncoate, Pa.

Application March 16, 1935, Serial No. 11,384

3 Claims. (Cl. 240—52)

This invention relates to lantern holders for road crossings and has as its object the production of a new and improved device for this purpose.

5 Lantern holders for lanterns which guard roads and particularly those which guard railroad crossings now in general use are objectionable because normal operating stresses, such as wind stresses and swaying due to the motion of the gate to which the holders are attached, cause the lantern bail and the lantern which it carries to rotate about an axis perpendicular to the plane of the road which the lantern guards with the result that the road light lens (hereinafter called 10 the signal light) is often at such an angle to the road that a person approaching the gate cannot see the signal light. Further, where the road meets the railroad at an angle other than a right angle, this angularity of the light lens with respect to the road is accentuated. For, in the 15 holders now in general use, it is not possible to adjust the bail so that it carries the lantern in such a manner that the light lens faces directly down the road which it is supposed to protect. And even if such an adjustment is attempted, it 20 is soon disturbed by the normal operating stresses which act upon the holder and the lantern which it carries. It is an object of my invention to provide a lantern holder which will 25 be free from the defects hereinbefore more particularly set forth, which will support the lantern in such a manner that it will not rotate about an axis perpendicular to the plane of the road which the lantern guards, and which can 30 readily be adjusted so as to support the lantern in such a manner that the signal light always faces directly down the road no matter at what angle the road meets the railroad.

It is a further object of this invention to provide a lantern holder having the novel characteristics hereinabove set forth which will also be easy to manufacture, assemble and use.

Each of the above objects is attained in the holder which I have shown in the accompanying drawings for the purpose of illustrating my invention and which I will now describe.

In the said drawings Figure 1 is a perspective view of a railroad crossing and a gate having my novel lantern holder attached thereto. The full lines show the gate, the lantern holder and lantern in the lowered position. The dot and dash lines show the gate and the elements which it carries in the raised position. The road is at 45 right angles to the railroad.

Figure 2 is a plan view of a fragment of the disclosure shown in Figure 1.

Figure 3 is a plan view of a crossing gate, lantern holder and lantern wherein the road is at an angle other than a right angle to the railroad. 5

Figure 4 is an enlarged plan view of a fragment of the gate, the lantern holder and the lantern shown in Figure 3.

Figure 5 is a plan view of my novel lantern holder. 10

Figure 6 is a front view of my novel lantern holder and the lantern carried thereby.

Figure 7 is a section taken along the lines 7—7 of Figure 6.

Referring more specifically to the drawings 15 wherein similar reference numerals denote similar parts reference numeral 1 designates my novel lantern holder as a unit which consists of the bracket 2, the hook and eye member 3, the bail 4, and the cotter pin 5. 20

The bracket 2 consists of the gate attaching arm 6 and the bail carrying arm 7. The gate attaching arm 6 has suitable apertures formed therein through which extend the screws 10, which serve to attach the arm 6 to the gate 33. 25 The arm 7 terminates in a loop 8, the aperture 9 of which receives the hook portion 14 of the hook and eye member 3.

The hook and eye member 3 consists of the two comparatively wide arms 13 which are bent 30 at their upper ends to form the said hook 14 and which are curved at their lower ends to define and form the long eye 15. The arms 13, the front arm of the loop 8, the hook 14 and the rear arm of the loop 8 have the registering apertures 16, 11, 17 and 12 respectively formed therein which receive the body portion 26 of the cotter pin 5 as shown. 35

The bail 4 consists of the vertical arms 18, the horizontal arms 23 which are twisted at 19, the 40 triangular loop 20 formed by the horizontal arm 21 and the arms 22, and the light attaching hooks 24.

To assemble my novel unit it is only necessary 45 to place the arm 21 of the bail loop 20 within the eye 15 of the hook and eye member 3, then position the hook portion 14 of the hook and eye member 3 within the aperture 9 formed by the loop 8, and then insert the cotter pin 5 through the registering apertures 16, 11, 17, 12 50 and then bend the free ends 27 of the cotter pin into the locking position as shown. To mount the lantern 28 in the bail 18 it is only necessary to insert the hooks 24 into the apertures 32 55

formed in the ears 31 of the lantern 28. To mount the ensemble upon a guard gate of a railroad crossing it is only necessary to insert the screws 10 through the apertures formed in the 5 arm 6 of the bracket 7.

The comparatively wide arms 13 which bound and form the comparatively long eye 15 of the hook and eye member 3 combine with the comparatively long arm 21 of the loop 20 of the bail 10 4 to prevent rotation of the bail 4 about an axis, such as JK, perpendicular to the plane of the road which is guarded by the gate 33. The angular structure of the loop 20 of the bail 4 diminishes the possibility of relative displacement of the arm 21 with respect to the eye 15. The twist 19 makes it possible to readily turn the arms 23 of the bail 4 so that they are parallel 15 to the road guarded by the gate 33.

It is believed to be obvious from the foregoing 20 description that a lantern carried by my novel lantern holder can readily be placed in the proper position with respect to the road which it is intended to protect and once so placed will always remain in the proper position with respect to the said road under all normal operating stresses. If the road meets the railroad at right angles, as shown in Figures 1 and 2, it is only necessary to mount the unit 1 and the lantern which it carries upon the gate 33. Since rotation 25 about an axis perpendicular to the plane of the road is not possible the lens 29 will always face directly down the line GH which is parallel to the direction BD of the road. If the road meets the railroad at some angle other than a right angle, as shown in Figures 3 and 4, it is only necessary to twist the arms 23 about the twist point 19 as a center and cause them to assume the position GH where they are parallel 30 with the direction BD of the road. Once in this position they will remain there under all normal operating stresses.

The above disclosure is to be understood as being by the way of illustration only and not by the way of limitation since many changes may be made in the disclosure here shown without departing from the spirit of my invention which consists in providing the hook member of a lantern holder consisting of a hook member and a bail, with a comparatively long bail receiving eye, in providing the bail of the said holder with a hook attaching loop the horizontal arm of which is substantially equal in length to the length of the bail holding eye, and in providing the said bail with a twist portion from which the bail attaching arms extend. 55

Having described my invention, what I claim as new and useful is:

1. A lantern holder for use in conjunction with a crossing guard gate consisting of an angular base member one of the angle-arms of which is adapted for attachment to the said gate and the other of the angle-arms of which terminates in a loop at its free end; a hook terminating at its lower end in a comparatively long bail receiving eye positioned within the said loop; and a bail carried by the said hook, the said bail consisting of two vertical lantern attaching arms, a horizontal arm extending inwardly from each of the said vertical arms the two said horizontal arms being twisted at their meeting point, and a hook attaching loop consisting of a horizontal arm and two angularly disposed arms extending upwardly from the first said horizontal arms, the said horizontal loop arm being positioned within the said bail receiving eye. 10 15 20

2. A lantern holder for use in conjunction with a crossing guard gate consisting of an angular base member one of the angle-arms of which is adapted for attachment to the said gate and the other of the angle-arms of which terminates in a loop at its free end; a hook terminating at its lower end in a comparatively long bail receiving eye positioned within the said loop; and a bail carried by the said hook, the said bail consisting of two vertical lantern attaching arms, a horizontal arm extending inwardly from each of the said vertical arms the two said horizontal arms being twisted at their meeting point, and a triangular hook attaching loop extending upwardly 30 35 from the said horizontal arms, one of the arms of the said loop being positioned within the said bail receiving eye. 25

3. A lantern holder for use in conjunction with a crossing guard gate consisting of an angular base member one of the angle-arms of which is adapted for attachment to the said gate and the other of the angle-arms of which terminates in a loop at its free end; a hook terminating at its lower end in a comparatively long bail receiving eye positioned within the said loop; and a bail carried by the said hook, the said bail consisting of two vertical lantern attaching arms, a horizontal arm extending inwardly from each of the said vertical arms the two said horizontal arms being twisted at their meeting point, and a hook attaching loop extending upwardly from said point of twist and positioned within said bail receiving eye. 40 45 50
